UNITED STATES PATENT OFFICE.

DIMOND C. NEWTON, OF OWEGO, NEW YORK, ASSIGNOR OF ONE-HALF TO MAX LINDEMAN, OF OWEGO, NEW YORK.

SAFETY AND SIGNALING DEVICE FOR RAILROADS.

1,092,383.

Specification of Letters Patent.

Patented Apr. 7, 1914.

Application filed October 23, 1913. Serial No. 796,758.

To all whom it may concern:

Be it known that I, DIMOND C. NEWTON, a citizen of the United States, and a resident of the city of Owego, county of Tioga, and 5 State of New York, have invented a new and useful Safety and Signaling Device for Railroads, of which the following is a specification.

The invention is adapted for use in connection with railroad lines, whether operated by steam, electricity, or other power, and has for its object the attainment of two-fold or dual results, one, that by the operation of the apparatus, notification is given 15 to the engineer or motorman that his train is passing from one block to another of the line and that the track is clear through the block about to be entered, and the other, that in the event the track is not clear, the 20 apparatus will automatically and without any attention or act on the part of the engineer or motorman, apply the brakes so that the train will be brought to a stop. In this way, the apparatus automatically protects 25 the train and the lives of the passengers, whether or not the engineer or motorman be neglectful of his duties, or perhaps be stricken with sudden illness, whereby he is rendered unable to perform his duties.

30 This present invention is an improvement upon that heretofore patented to me in and by United States Letters Patent, No. 1,073,510 dated September 16, 1913, in that the apparatus is materially simplified and its cost 35 reduced. In this invention, as in that heretofore patented to me and above referred to, electrically operated appliances are carried by the locomotive, electric car, or other engine, which are brought into circuit and 40 hence into operation by means of certain circuit closing devices upon the track and their counterpart devices carried by the locomotive or other engine, and these electrical appliances are so constructed that in the 45 first instance an appropriate signal only is given to the engineer that a block is just about to be entered and that the track in it is clear, and, as a secondary operation, if the

track be not clear, then certain apparatus actuated in part by the same mechanism as 50 that which operates the signaling apparatus, will be called into operation, with the result that the brakes will be automatically applied and the moving train brought to a stop without any act on the part of the engineer or motorman. 55

The drawing hereof illustrates diagrammatically the construction and method of operation of the parts.

In the drawing, 1 represents an electric 60 bell provided with suitable operating devices, preferably inclosed within a suitable casing 2.

3, 3' are conductors connecting the bell with suitably constructed shoes 4, 4'. 65

5 is a sufficiently powerful magnet connected by conductors 6, 6' with the conductors 3, 3' as shown. When energized the magnet exerts its attractive force upon a lever 7 which is normally retracted by a 70 spring 8. The lever, when drawn downwardly by the magnet, releases a locking pawl 9, which in turn releases a drum 10, or its equivalent, whereby through appropriate apparatus and in a manner well understood, the brake shoes of the train are 75 called into action.

11, 11 are set screws for the proper adjustment of the lever 7.

All of the parts thus far described are 80 mounted upon or carried by the locomotive or other engine or machine.

12 and 13 are rails of the track which is divided electrically into blocks or sections by insulating material 14, or in any other 85 preferred manner.

15 and 16 are contact rails, preferably laid in the roadbed between the rails 12 and 13 and so located and of such length as to properly engage the contact shoes 4, 4' carried by 90 the locomotive or other engine when during its movement they pass over the contact rails.

17 is a battery of sufficient power to actuate the brake applying mechanism above 95 described.

18 is a conductor connecting one end of the battery with the contact rail 15. 19 is another conductor connecting the other end of the battery with the track rail 13 in 5 the next adjoining section.

20 is a suitable resistance coil provided with a conductor 21 which connects one end of it with the contact rail 16. 22 is another conductor which connects the other end of 10 the resistance to the conductor 19 and 23 is another conductor which connects the resistance with the track rail 12 in the next adjoining section.

The operation is as follows: As the locomotive or other engine proceeds along the track in the direction indicated by the arrow, 15 the contact shoes 4, 4' engage with the contact rails 15, 16, whereby, in a manner well understood, the battery circuit will be closed 20 as follows: from the battery through conductor 19, through conductor 22, through the resistance 20, through conductor 21 to contact rail 16, to contact shoe 4', through conductor 3' to the bell, through conductor 25 3, shoe 4, contact rail 15 and conductor 18 to the other pole of the battery. It will be noted that in this circuit the current passes through the resistance 20. Hence the power 30 of the battery is reduced so that it is only sufficient to ring the bell and not to apply the brake mechanism. Thus the battery being located near the end of one of the insulated blocks of the railroad, the ringing of the bell will give notice that the train is 35 just entering a new block, and also that all the apparatus involved in the system is in good working order, and if the ringing of the bell is the only thing that happens, then the engineer or motorman will know that 40 the block just about to be entered is clear of obstruction; if, on the other hand, there be another train, locomotive, or car stalled or in motion in the block about to be entered, then the circuit from the battery will be as 45 follows: through conductor 19, track rail 13, through the wheels and axles of the train or other obstruction to track rail 12, through conductor 23, to conductor 21, to track rail 16, to contact shoe 4', through conductor 3' 50 to the bell, and, since the resistance 20 has now been cut out, rendering the full power of the battery available, the current will likewise pass through conductor 6' to magnet 5, whereby it will be energized and the 55 lever 7 actuated, thus the automatic brake mechanism will be released and the brakes applied. The current passes thence from the other end of the magnet through conductor 6 to conductor 3 to contact shoe 4 to 60 contact rail 15 and through conductor 18 back to the other end of the battery. Since the full power of the battery is now applied, not only will the bell ring in the cab, but

also, as stated above, the brake mechanism will be released and the brakes automatically applied without any action or thought on the part of the engineer or motorman and the oncoming train will be brought to a stop. It is probable that during this second or brake applying operation, some current will pass from the conductor 19 to conductor 22 to and through the resistance 20, but that will be incidental merely and have no effect upon the above stated operations of the parts.

The drawing is diagrammatical merely, the parts being somewhat separated in order that the illustration may be more easily and plainly noticed. In actual practice the battery may be located between the track rails, 80 or by the side of the track or in any other preferred place and protected against the elements by a suitable housing of any kind and also to obviate the difficulties arising from ice, snow or other matter falling upon the contact rails 15, 16, which might interfere with the proper electrical contact between them and the shoes 4, 4' they may be protected with any suitable covering, the contact shoes 4, 4' being correspondingly 85 constructed, all as is well known and practised in this art. It is not necessary to illustrate either of the above recited features.

It will be obvious to those who are familiar with such matters that the details 95 of construction and method of arrangement of the parts may be very greatly modified without departing from the essentials of the invention. I therefore do not limit myself to such details.

I claim:

1. Railway safety and signaling apparatus for block system roads embodying track-rails in each block insulated from those in the adjoining blocks, a battery and stationary contact devices for each block, each battery being directly connected with one of the stationary contact devices of one block and with one of the track-rails of an adjoining block, a conductor connecting the other contact device of each block with the other track-rail of the adjoining block, a resistance interposed between said conductor and the connection of the battery with the track-rail, and signaling devices, automatic brake mechanism and circuit-closing devices co-operating with said contact devices and carried by the engine, for the purposes set forth.

2. Railway safety and signaling apparatus for block system roads embodying track-rails in each block insulated from those in adjoining blocks, a battery and stationary contact devices for each block, each battery being directly connected with one of the stationary devices of one block and with one

of the track-rails of an adjoining block, a conductor connecting the other contact device of each block with the other track rail of the adjoining block, and a resistance in-
5 terposed between said conductor and the connection of the battery with the track-rail, for the purposes set forth.

In testimony whereof I have signed my name to this specification in the presence of two subscribing witnesses.

DIMOND C. NEWTON.
